UNITED STATES PATENT OFFICE

ROYCE S. BUNKER, OF BALTIMORE, MARYLAND, ASSIGNOR TO W. & J. KNOX NET AND TWINE COMPANY, OF BALTIMORE, MARYLAND, A CORPORATION OF NEW JERSEY

TENNIS NET

Application filed December 4, 1931. Serial No. 578,950.

This invention relates to nets, as tennis nets, which are provided with a marginal band usually for the suspension thereof, and it has for its object to improve this portion 5 of such a net. Ordinarily this portion of the net is formed by a two-ply band, as duck, which receives between its plies the margin of the net proper, the two plies and net proper being secured together by stitching 10 penetrating all three and extending lengthwise of the band. This construction is faulty in that it frequently happens that one or more strands will be cut by the stitching needle so that if such strands are not disrupted at once they will at least be so far 15 weakened as to break when the net is in service; nor can the cuts usually be detected by the manufacturer unless a strand is completely severed because where they occur the 20 strands are concealed by the plies of the band. My object is to provide a tennis net which will be free of this fault and which further will be stronger and more durable in general 25 than ordinary tennis nets and superior thereto in certain other respects.

Two forms of my invention are shown herein by way of example. Both are characterized by the securing of the band plies or layers to the margin of the net proper, 30 which intervenes between them, at spaced points arranged successively lengthwise of the band and alternating with the strands, as by means of rivets. Both are also characterized by said plies or layers reaching 35 beyond the net proper and having their free edges extending in opposite directions and lapping each other and thereupon secured together thus to form as it were a two-ply saddle to straddle the cable which shall be 40 devoid of any outstanding seam or welt that would exist if the two edges extended in the same direction and were secured together in that arrangement; but in one of these forms the two plies are constituted by separate 45 pieces whereas in the other form they are parts of a single piece, the portion of the piece intervening between the plies being itself folded lengthwise so as to arch over the cable. In the preferred form, as indicated, I use rivets 50 as the means to secure the said band plies

or layers to the margin of the net proper, and I use them in such a way that they are not only not visible in the finished net but that any surface-unevenness that they might otherwise produce at the exposed faces of 55 the band is avoided; the construction is also further such that any surface-unevenness that might otherwise be due to the presence of knots of the net proper being between the plies is avoided at the exposed faces of the 60 band.

In the drawing.

Fig. 1 shows a tennis net and its cable in elevation and in the first-mentioned form thereof;

Fig. 2 is a vertically sectional perspective view of such form;

Fig. 3 is a section on line 3—3, Fig. 2;

Fig. 4 shows a tennis net and cable in elevation and in the other form;

Fig. 5 is a vertically sectional perspective view of such other form; and

Fig. 6 is a section on line 6—6, Fig. 5.

Referring, first, to the first form:

1 is the net proper and 2 the cable.

The band is here composed of two separate plies 3, 4 of suitable strong fabric, as duck, usually employed to form the top band of a tennis net, and these are in this example secured to the net proper as follows: Having 80 lapped outward, as at 5, longitudinal edge portions of the said plies and placed the plies against the opposite faces of the upper marginal portion of the net proper so that the folds of the laps project upwardly, the two 85 plies are riveted to each other and the net proper by rivets 6 penetrating all three, 7 being washers on the rivets. The rivets are placed, as shown, one after another lengthwise of the band and each so as to penetrate 90 an opening of the mesh of the net and clear of the strands thereof. The two plies are then folded outwardly and upwardly, as at 8, and finally their upper and projecting edge portions are bent in opposite directions and 95 made to lap each other as shown at 9 and are secured together along a line or lines extending lengthwise of the plies, as by stitching 10 (a stitching machine adapted to perform such work on the eventually tubular band 100

being known and requiring no description here); the lap is so positioned that when the cable 2 is present in the band the lap will rest on the cable and so form, as it were, 5 the saddle portion of the band, which of course increases the durability of the band at this point. Usually the edge of that ply which laps outward of the other ply at the top of the band will be lapped on itself, as 10 at 12, so as to avoid the presence of an exterior raw edge.

Thus I not only avoid any possibility of strands of the net being cut in assembling the band with the net proper but the net is made 15 exceedingly strong and durable, largely because at the points where wear is most likely to manifest itself—at the top and bottom of the band—there are two or more thicknesses of material. By attaching the plies to the 20 net proper as disclosed the rivets or other attaching means 6 are at once obscured by the plies and also unevenness at the exterior faces of the band is substantially eliminated.

In the form shown by Figs. 4 to 6 the same 25 advantages accrue. The two plies 13 and 14 are integral parts of the same strip of fabric which is folded midway its width and lengthwise, as at 15, and receives between the layers 13a and 14a thus resulting the upper 30 edge portion of the net proper 1 to which said layers are secured by rivets 16 arranged one after another lengthwise of the strip and each so as to penetrate an opening of the mesh of the net and clear of the strands; then the 35 flanking or marginal portions of the strip are folded upwardly and outwardly to produce the two plies 13 and 14 and their edge portions are bent in opposite directions and made to lap each other, as at 18, and secured 40 together along line or lines extending lengthwise of the plies, as by stitching 19, so that preferably the lap will rest, saddle-fashion, on the cable when the same is introduced; the outer edge portion may be lapped inwardly, as at 20, to avoid a raw edge.

Salient and independently novel features of my invention are the folding of elongated plies—secured to the interposed net proper margin by means penetrating the plies and 50 net proper and arranged lengthwise of the plies—outwardly from the net proper and so as to extend beyond said margin, together with securing of the plies together beyond said margin, whether or not their upper 55 edges project oppositely and lap each other and whether or not as so folded they cover the securing means; the projection of the outer or free edges of plies in opposite directions and the lapping and securing of them 60 together, however the plies may be otherwise formed and assembled with the interposed margin of the net proper; and that formation of such a net which is substantially shown in Figs. 4 to 6 and characterized by 65 a lengthwise substantially midfold in an

elongated fabric strip, means to secure the two adjoining layers thus resulting to the interposed margin of the net proper, the folding of the margins of the strip outwardly and so as to project beyond the margin of the net proper, and means to secure said strip margins together above the margin of the net proper.

Having thus fully described my invention 75 what I claim is:

1. A net of the class described comprising a net proper, two elongated fabric plies extending lengthwise of and between which a margin of the net proper is interposed, means penetrating the plies and the net proper and arranged lengthwise of the plies, for securing the plies and net proper together, said plies being folded outwardly from the net proper and as so folded extending beyond said margin thereof, and means to secure the plies together beyond said margin.

2. A net of the class described comprising a net proper, two elongated fabric plies extending lengthwise of and between which a margin of the net proper is interposed, means, penetrating the plies and the net proper and arranged lengthwise of the plies, for securing the plies and net proper together, said plies being folded outwardly from the net proper and as so folded extending beyond said margin thereof and projecting at their free edges in opposite directions and lapping each other, and means to secure the lapping portions of the plies together.

3. A net of the class described comprising a net proper, two elongated fabric plies extending lengthwise of and between which a margin of the net proper is interposed, a series of independent means, arranged lengthwise of the plies and penetrating them and the openings of the mesh of the net proper at points removed from all the strands of the latter, for securing said plies and net proper together, said plies being folded outwardly from the net proper and as so folded extending beyond said margin thereof and projecting at their free edges in opposite directions and lapping each other, and means to secure the lapping portions of the plies together.

4. A net of the class described comprising a net proper, two elongated fabric plies extending lengthwise of and between which a margin of the net proper is interposed, said plies extending beyond said margin and projecting at their outer edges in opposite directions and lapping each other, and means to secure the lapping portions of the plies together.

5. A net of the class described comprising a net proper, two elongated fabric plies extending lengthwise of and between which a margin of the net proper is interposed, means, penetrating the plies and the net proper and arranged lengthwise of the

plies for securing the plies and net proper together, said plies being folded outwardly from the net proper and as so folded covering said means and extending beyond 5 said margin of the net proper, and means to secure the plies together beyond said margin.

6. A net of the class described comprising a net proper, a fabric strip folded upon itself substantially midway of its width and receiving between the two thereupon adjoining layers thereof a margin of the net proper, means to secure said layers to said margin lengthwise of the strip, the strip having its own marginal portions folded outwardly and 15 projecting beyond said margin, and means to secure together the edges of said marginal portions of the strip outward of the margin of the net proper.

20 In testimony whereof I affix my signature.
